(57) **CLAIM**

The ornamental design for a chair arm, as shown and described.

DESCRIPTION

FIG. 1 is a perspective view of a chair arm in a first position from a first point of view, according to a first embodiment. FIG. 2 is a front view of the chair arm in the first position, according to the first embodiment.

FIG. 3 is a back view of the chair arm in the first position, according to the first embodiment.

FIG. 4 is a right side view of the chair arm in the first position, according to the first embodiment.

FIG. 5 is a left side view of the chair arm in the first position, according to the first embodiment.

FIG. 6 is a top view of the chair arm in the first position, according to the first embodiment.

FIG. 7 is a bottom view of the chair arm in the first position, according to the first embodiment.

FIG. 8 is a perspective view of the chair arm in a second position from the first point of view, according to the first embodiment.

FIG. 9 is a perspective view of a chair arm in a second position from the first point of view, according to a second embodiment.

FIG. 10 is a front view of the chair arm in the first position, according to the second embodiment.

FIG. 11 is a right side view of the chair arm in the first position, according to the second embodiment; and,

FIG. 12 is a perspective view of the chair arm in the second position from the first point of view, according to the second embodiment.

The broken line showing is included for the purpose of illustrating unclaimed subject matter and forms no part of the claimed design.
